[57] CLAIM

The ornamental design for a towel rack with swingable arms, as shown and described.

DESCRIPTION

FIG. 1 is a front, top right side perspective view of a towel rack with swingable arms showing my new design;

FIG. 2 is a left side elevational view thereof;
FIG. 3 is an enlarged fragmented top plan view thereof,
the bottom view being substantially identical;
FIG. 4 is an enlarged front view thereof; and,
FIG. 5 is an enlarged rear view thereof.

FIG. 1

FIG. 2

FIG. 3

FIG. 4

FIG. 5
